UNITED STATES PATENT OFFICE.

WILFRID V. N. POWELSON AND WARREN TRAVELL, OF NEW YORK, N. Y.

ALIGHTING MEANS FOR LIGHTER-THAN-AIR SHIPS.

Application filed September 6, 1921. Serial No. 498,607.

This invention relates to improvements in alighting means for lighter-than-air ships. Up to the present time, airships of large size have never been brought safely to rest on land or water without the assistance of a large number of attendants. It is an object of this invention to provide means whereby an airship may safely alight on either land or water and without the assistance of any attendant whatever.

Airplanes have been commonly equipped with wheels for running on the ground but if an airship were equipped with the same type of wheels and wheel attachments as those used on airplanes, there would result, on landing, stresses which would distort or destroy the structure of the airship. We have invented a means in connection with the use of landing wheels whereby the weight of the airship is distributed among several wheels, regardless of unevennesses of the surface of the ground and whereby the stresses produced in the structure of the airship, due to its weight being supported by these wheels, are kept within predetermined limits.

We also apply the same means or a modification thereof to permit the safe alighting of an airship on the surface of a body of water and for the prevention of the destruction of the airship due to wave action while the airship is floating on water.

Also, our invention provides improved means for withdrawing the alighting wheels within the envelope of the airship during flight.

These several objects are attained in our improvement by attaching wheels to an airship along the lower part thereof, by means of arms which are pivotally connected to the airship. Pockets are provided in the exterior envelope, into which these wheels with their supporting arms may be withdrawn during flight. Previous to alighting, the wheels are let down, the arms being provided with limit stops which prevent the wheels from being lowered too far. The wheels are held in this lowered position by means of a spring, or other device, exerting an approximately constant force, predetermined in amount. The structure of the airship may be designed to transmit different loads to different wheels when resting or running on ground or water. Assuming that the design is such that the wheels are to take approximately equal loads, when the airship alights

on an uneven surface of ground, the wheels will be raised to different elevations by the unevenness of the ground, but each wheel will carry no more than its own proportion of the weight of the airship, producing in the airship structure no more than the predetermined stresses. It should be noted that even a large airship on alighting may have a weight only slightly in excess of the weight of the air displaced thereby and that the actual load to be carried by each wheel may be no greater than the load which is carried by a landing wheel of a much smaller airplane receiving no support from lighter-than-air gas.

Such wheels may be used on an airship not only for alighting, but may be used in connection with airships, heavier-than-air and equipped with lifting planes, to run along the ground and thus obtain proper speed, so that the lifting planes at such speed may raise the airship from the ground. This method of launching an airship permits the loading of the airship beyond the lifting power of its gas and enables an airship of a given size to carry a much greater load either of fuel or cargo than it could otherwise carry. Such an advantage alone is of prime importance in the successful financial operation of a commercial line of airships.

For alighting on water and supporting the unbalanced weight of an airship thereon, the wheels may be of larger size and fitted with water-tight air chambers, thereby providing a buoyancy for each wheel equal to or in excess of the load which it is designed to carry. These wheels may have their outside rims adapted for running on the ground, so that, when thus equipped, an airship may alight either on land or water. When an airship is floating on water, supported by such wheels, the effect of waves will be to cause the various wheels to rise and fall with the wave motion, but each wheel can transmit to the structure of the airship no greater stress than is determined by the force of the spring or other device which holds it downward. At the same time, the airship is supported at such elevation above the water surface that the fragile envelope of the airship escapes the destructive force of the waves. Without such a resilient means of support, even small waves would produce in the structure of an airship stresses far greater than airships can withstand as at present designed or, if designed

to resist such stresses, the weight of the structure would probably have to be so increased as to be prohibitive.

With airships thus provided with alighting wheels, the cost and difficulty of obtaining suitable mooring stations will be greatly reduced. Bays, rivers and lakes having suitable area and protection from the wind may be used as intermediate and terminal stations, or if there exists no such body of water in a locality where a station is desired, a dike can be built around a swamp or low lying piece of ground and an artificial pond created at much less cost than would be encountered in the purchase and leveling of an equal area of ground, free from water, as would be required for the manipulation of airships according to present methods of operation.

In the practical application of the invention thus set forth, various devices may be employed in substitution for those which are herein shown as illustrating the principles involved; and variations may be made in many respects without departing from the scope of the invention. It is intended that the patent shall cover by suitable expression in the appended claims whatever features of patentable novelty exist in the invention disclosed.

In the accompanying drawings, which are somewhat diagrammatic:

Fig. 1 is a side elevation of an airship equipped with alighting wheels;

Fig. 2 is a side elevation of a portion of the same to a larger scale and shows an alighting wheel in its lowered and raised positions;

Fig. 3 is a cross sectional view on line 3—3 of Figs. 1 and 2;

Fig. 4 shows the alighting wheel on a still larger scale with means for providing resiliency, being a longitudinal section through one of the pockets;

Fig. 5 is an end elevation of the same; and

Fig. 6 is a sectional view of a wheel adapted for alighting on both land and water.

In Fig. 1, the airship 1, with its power car 2 is shown supported by wheels 3 on a ground surface. These wheels are distributed along the length of the ship, and are in rows, one at each side, as seen in Fig. 3.

In Fig. 2 a wheel is shown in its lowered position, when the ship is supported by arms 4, and in raised position at 3', when the wheel is retracted within pocket 5, within the envelope 6 of the airship, as when in flight.

Figs. 4 and 5 on a larger scale show the spring 9 which holds the wheel with approximately constant force in a downward position, the stop 7 preventing it being pulled downward further than is desirable. The spring and stop cooperate to set the arm 4 in an obliquely, trailing position so that it can both transmit weight to the ground, and yield to the rear and upward on encounter-

ing an obstacle when running forward. The spring is shown attached to the arm 4 by a rope 10 passing around a sheave 11 supported by a bracket 18 attached to a cross beam 15 forming part of the framework. The latter, as illustrated, is so positioned with respect to both the axle 8 and the short arm of arm or lever 4, that the perpendicular distance from the axle or fulcrum 8 to the line of the rope 10 is substantially the same at both of the illustrated limits of movement. This makes it possible, with a suitably chosen spring 9, to maintain a constant limit for the supporting effect of the wheel on the airship no matter whether the wheel is in its lowest position, as shown in full lines, or in its high dotted position; and this is also approximately true of any intermediate position. This is obvious mathematically upon computing a moment equation about the axle 8, and noting that the moment arm from axle 8 to the line of the vertical thrust or supporting force acting vertically through the wheel varies in proportion to the change in the spring strength as the latter is elongated or shortened by the swing of the lever or arm 4. Since these elements vary proportionally, and the moment arm from axle 8 to the force acting along the rope 10 remains approximately constant, it must follow that the remaining element of the moment equation, namely, the supporting force or vertical thrust at the wheel, must also be constant. Accordingly the invention enables the limit of supporting effect of each wheel to be predetermined and to be maintained constant. Until this limit is reached the wheel occupies the full line position illustrated; and the total pull of the spring is resisted either at the stop 7 or at the ground, or in part at each, as the case may be; but when this limit is reached the wheel is swung upward about the axle 8. That is, when the weight of the ship rests on the wheel too heavily the spring yields; the other wheels take up the load, the ship first settling lower if they are not already touching ground; and the load is thus distributed among them all. The springs keep each single wheel 3 extended so as to carry its full part of the load, and to prevent it from transmitting undue stress to its part of the frame. Various other means may be employed for accomplishing the same result. The axle 8 about which arm 4 rotates to position 4' is supported by a bracket 19 attached to a beam 14 which is part of the structure of the airship. There is shown a hook 12, attached by rope 13 to the structure, for holding the wheel in its retracted position 3'. For withdrawing the wheel into the envelope a rope 13' may be provided as a continuation of rope 13, around a sheave 12', which may be operated from any convenient place above in the body of the ship.

In Fig. 6, the wheel 3 is shown with a tread

16 adapted for running on a ground surface, and with a water-tight air compartment 17 which provides buoyancy when floating on water.

5 When the invention is applied to a lighter-than-air ship which is heavier with its load than the air it displaces, the ship may have integral air-planes to carry the excess weight in flight and these wheels will carry on land 10 the amount by which the weight of ship exceeds the buoyant force.

What we claim is:

1. The combination, with an airship containing lighter-than-air gas, of a multiplicity 15 of landing supports therefor distributed fore and aft along its underside; said supports each comprising a ground engaging member mounted on and extensible from the frame of the ship and adapted to yield toward it at substantially constant pressure upon contact 20 with the ground; a stop arranged to limit the travel of said member from the frame; a spring having operating connection with said member and anchored to a rigid part of the frame in position for holding said member against said stop with a pressure sufficient 25 for the said member to support a limited portion of the weight of the airship without yielding; the mounting of said member and its spring being adapted for said member to yield when the ground pressure upon it exceeds said limit.

2. In an airship containing lighter-than-air gas, and having a multiplicity of ground 30 engaging supports distributed over and attached to the lower portion of said airship, means for distributing the landing stress of the airship among the several supports comprising, as a part of each said support, a lever having a ground-engaging end, a spring, and connections between the lever, the spring and the body of the airship whereby, upon sustaining a ground pressure of predetermined amount the support yields toward 35 the body of the ship, and the said connections are arranged to provide for said pressure to be at a certain spring position, with thereafter during the yielding such little increase of resistance to ground pressure as to let the ship drop until increased proportion of 40 ground pressure results on other supports.

3. The combination, with an airship containing lighter-than-air gas, of a multiplicity 45 of yielding supports distributed fore and aft over the underside of the ship each comprising a ground-engaging member, a spring for said member, and connections between the member, spring and the frame of the airship; each yielding support having a ship-supporting strength commensurate with the landing stresses arising from the particular portion of the ship where the particular support is located, and each yielding support being constructed, mounted on and connected 50 to the ship so that for landing stresses, higher

than said commensurate stress, the support yields without substantial increase of its ground pressure.

4. Supporting means for air craft comprising a ground-engaging member mounted on and extensible from the craft supported, and adapted to yield toward the said craft upon contact with the ground; a spring; and leverage connections between said spring, member and the craft supported, including a swinging element, to a swinging part of which the said spring is secured, and means comprised in the relation of the spring to said element whereby the spring, acting upon the ground member through said element, holds said member in repose until a predetermined load is carried by said member and then permits said member to yield without further repose when said load is exceeded notwithstanding that the load remains substantially at said predetermined value at which said yielding is initiated.

5. Supporting means comprising a ground engaging member adapted to yield toward the thing supported, and means for maintaining constant the pressure of said member on the ground, during its yielding, irrespective of its degree of yield toward the thing supported, comprising a pivoted support for said member; means applying force to said member to oppose its yielding and means interposed between the last said means and the member whereby the moment of said opposing force about the pivot of the support counterbalances the moment of said ground pressure about said pivot during the yielding of the member.

6. Supporting means for an airship comprising a ground engaging wheel; a lever, carrying the wheel and fulcrumed on the airship so as to permit the wheel to move toward it; and spring means secured to the airship and having connection with said lever; and means controlling the application of the spring force whereby the moment of resistance at the end of yielding is approximately the same as at its beginning.

7. Supporting means for an airship comprising a lever fulcrumed on the airship and having a yieldable connection therewith including a spring, and a wheel mounted on said lever in ground engaging position and movable therewith about the fulcrum toward the airship; and guiding means for said yieldable connection providing for change of the spring force substantially in proportion to the change in the horizontal component of the distance between said fulcrum and the wheel.

8. Supporting means for an airship comprising a ground engaging wheel; a lever carrying said wheel and being fulcrumed to permit the wheel to move toward the airship; a spring force, acting on said lever; and means whereby the moment arm of said

spring about said fulcrum remains approximately constant during the turning of the lever; said spring force varying in proportion to the moment arm of the force transmitted by the wheel, whereby the latter force is maintained substantially constant during movement of the wheel toward the airship.

9. Supporting means comprising a ground engaging member adapted to yield toward the thing supported; force exerting means attached to the thing supported, having connection with said member; and guiding means for said connection whereby the force exerted by the force exerting means on the member increases in proportion as the moment arm of the ground pressure on the said member increases during the yielding.

10. Supporting means comprising a ground engaging member adapted to yield toward the thing supported; a lever pivoted intermediate of its ends on the thing supported and carrying said member on one of its arms; a spring attached to the thing supported having connection with the other arm of said lever and adapted to yield at a predetermined pressure upon the member; and guiding means for said spring connection whereby as the lever swings the said predetermined pressure is maintained.

ed having connection with the other arm of said lever and adapted to yield at a predetermined pressure upon the member; and guiding means for said spring connection whereby as the lever swings the said predetermined pressure is maintained. 25

11. Supporting means comprising a ground engaging member adapted to yield toward the thing supported; a lever pivoted intermediate of its ends on the thing supported and carrying said member on one of its arms; a spring attached to the thing supported having connection with the other arm of said lever and adapted to yield at a predetermined pressure upon the member; and guiding means for said spring connection whereby as the lever swings the angle between said connection and the lever remains substantially unchanged. 30
